UNITED STATES PATENT OFFICE.

JAMES OCHS, OF READING, PENNSYLVANIA.

CIGAR-END CUTTER.

SPECIFICATION forming part of Letters Patent No. 243,956, dated July 5, 1881.

Application filed May 7, 1881. (No model.)

To all whom it may concern:

Be it known that I, JAMES OCHS, of the city of Reading, county of Berks, State of Pennsylvania, have invented a new and Improved Device for Trimming Cigar Ends, of which the following is a full, clear, and exact description, which will enable those skilled in the art to make and use the same, reference being had to the accompanying drawings, forming part of this specification, in which—

Figure 1 represents a side elevation of my improvement in cigar-trimmers; Fig. 2, a plan or top view of the same; Fig. 3, an end view explanatory of the force transferred from the handle to the knife.

Similar letters refer to similar parts.

This invention relates more particularly to the class of counter-machines used by the dealers generally for cutting or trimming to length the butts or thick ends of the cigars, whereby a neater appearance is presented and the length rendered more uniform.

The improvement consists of the usual grooved bed or base, A, of wood, to the end of which is secured the cast-iron frame B, provided with a recurved seat, B', a guide concentric with the fulcrum D², and struck with a radius therefrom, B², fulcrum-arm and hub B³, wearing-face C, and stud b for spring g.

D is the knife-lever, having its handle E projected at right angles and about one inch away from the face C, and provided with a guide-hook, D', and a triangular knife, F, dovetailed into the same, pivoted by the bolt D² to the fulcrum-arm B³, and is further provided with a stud, d, on the under side of the guide-hook D'. A spiral spring, g, is placed over the stud b on the frame B, and under the guide-hook D' upon the stud d. This keeps the arm or lever D raised ready for operation.

The base-block A may be marked as shown, or a movable gage may be attached, if deemed necessary. Usually they are not thought of sufficient importance to be applied.

The guide B² has a projecting stop or hook, B⁴, which prevents the rising of the lever beyond a defined point. The studs b and d are arranged to contact after the knife has trimmed the end of the cigar, and thus arrest the downward movement of the lever D.

The operation of the machine is as follows: A cigar is placed in the groove A', with its end resting in and projecting the required distance beyond the face of the recurved seat B'; a quick movement is given to the lever D by pressure on the handle E, which, being outside of the center line of the lever, tends to throw the cutting-edge of the knife F in close contact with the face C. This insures a clean cut, no amount of wear upon the points detracting from this tendency to a close fit between the shearing-surfaces, for, as shown in Fig. 3, the knife-edge will always contact closely with the face C, the guide B², through the hook D' of the lever, keeping the top edge of the same close to the frame and acting as the fulcrum for transferring the force from the handle E to the lower edge of the knife F.

I am aware that cigar-end trimmers have been attached to a table grooved to receive the cigars; that it is customary to have one edge of the groove graduated; that the frame of the cutter was generally provided with a curved bed corresponding with said groove, with which the knife contacted in making the cut; that springs were used for the purpose of raising the lever after each cut, and that triangular blades have been used for the purpose of securing a shearing cut, previous to my improvement. Therefore I do not broadly lay claim thereto. Nevertheless, I believe I am the first to embody a cigar-end trimmer in the form shown and to operate it in the way described.

Having described my invention, I claim as new and desire to secure by Letters Patent—

The device herein described, consisting of the table A, frame B, provided with a recurved seat, B', concentric guide B², arm B³, stop B⁴, and stud d, a lever, D, having a guide-hook, D', and stud b, with a spiral spring, g, common to both frame B and lever D, all combined substantially as specified, and arranged to operate in the manner shown and for the purpose set forth.

JAMES OCHS.
